UNITED STATES PATENT OFFICE.

OTIS T. GREGG, OF HACKENSACK, NEW JERSEY.

CANE-CAR ATTACHMENT.

Application filed June 2, 1924. Serial No. 717,242.

To all whom it may concern:

Be it known that I, OTIS T. GREGG, a citizen of the United States, residing at Hackensack, Bergen County, New Jersey, have 5 invented new and useful Cane-Car Attachments, of which the following is a specification.

This invention is designed primarily for cane-cars of the type which has one or more 10 side-doors hinged at the top to swing outwardly, and is provided with a lever-arm for operating suitable means, such as a turn-bar carrying offsets, for holding the doors in closed position. The present invention 15 comprises the combination with the foregoing of a pair of readily-engageable and readily-releasable complementary latching-members for maintaining said lever-arm in its door-holding position, with or without 20 readily-releasable automatic locking-means for locking said complementary members in engagement. The invention further comprises said novel complementary latching-members; also said automatic locking- 25 means; and also the various combinations and features set forth in the appended claims.

The broad invention is susceptible of embodiment in various forms and arrangements. The invention will be best understood, however, by reference to the ensuing detailed description and the accompanying drawings, in which a preferred embodiment of the invention will be set 35 forth.

In the accompanying drawings:—

Fig. I is an elevation, illustrating a portion of the side of a cane-car of the type referred to, with its swing-doors closed; 40 Fig. II is a perspective view, on a larger scale, showing a portion of the outer face of one of the car-standards, the upper portion of the aforesaid lever-arm, on which is mounted the relatively-movable latching-member in its position of engagement with the complementary latching-member; and 45

Fig. III is a similar view of the reverse or inner face of said standard, showing a hook-portion of said latch engaging the relatively-stationary latching-member, and also the preferred embodiment of the automatic locking-means aforesaid.

In the particular embodiment illustrated, 1 represents a portion of a cane-car, having upright standards 2. The car may have one or more side-doors, as 3 and 3', hinged

at the top to swing outwardly. As here shown, the doors are grille-doors, whose vertical members are hinged at the top to the car-body, and are connected at the bottom by a horizontal member, and may be braced by one or more (diagonal) brace-members. In the particular embodiment shown, there is a series of staples or other suitable bearings, as 4, 4, etc., secured to the longitudinal sill of the car-body, in horizontal alignment below the bottom of the door; and in these staples is journalled the turn-bar 5, which in this particular embodiment has a plurality of offsets, as 6, 6, 60 here shown as double cranks or loops, arranged to bear against the outer face of the lower part of the door when closed. However, if preferred, the turn-bar might be journalled in bearings secured to the door 65 itself, and carry offsets in the form of hooks adapted to engage staples or other complementary seats carried by the bottom-sill of the car-body. In either form of arrangement, the turn-bar is bent at a right-angle 70 to constitute the aforesaid lever-arm 7 which, in the preferred embodiment shown, is adjacent to and (when in its door-holding position) substantially parallel with one of the car-standards 2, preferably at one corner of the car-body. 75

In the preferred embodiment the relatively-movable latching-member is carried upon the upper portion of this lever-arm; and, as here shown in Fig. II, the lever-arm is bent at a right angle to constitute the horizontal handle 8, upon which is pivoted a latch 9, arranged to engage the relatively-stationary latching-member, as by entering an opening 10 (here shown as a vertical slot) in the standard, so that its downturned hook 11 can engage the relatively-stationary latching-member, such as a ledge 11', afforded by the reverse or inner face of the standard, as seen in Fig. III. The latch 9 not only pivots on the handle 8, but is freely movable sidewise thereon, so that it can be inserted into the slot in case the parts (such as the lever-arm or the handle) have been distorted as by collision from 95 a cane-cart. 100

In case the car has only two swing-doors, the lever-arm 7 for one door is opposite the adjacent end-standard 2, and the lever-arm for the other door is adjacent the other end-standard. In case the car have three or more swing-doors, the turn-bar 5' for the 110

intermediate door 3' may be extended to present its lever-arm 7' opposite the end-standard 2 and be journalled in bearings 4'-4'', etc., aligned slightly below the bearings 4 of the end-door 3, with its latch 9' positioned to enter a second slot 10' in staggered relation to the first-named slot 10. Indeed, even where the car has only two swing-doors, the lever-arms may be positioned to come opposite an intermediate or end car-standard.

Although the relatively-movable latching-member has been disclosed as pivoted on the horizontal handle, to enter a vertical slot 15 so its down-turned hook can engage against a relatively-stationary part of the car-body, nevertheless the horizontal handle 8 may be dispensed with, and the latch pivoted upon a diagonal handle or even upon the upper 20 portion of a straight lever-arm, to engage a correspondingly-arranged relatively-stationary latching-member. Moreover, the relatively-movable latching-member may be pivoted upon the door itself or upon the car- 25 body, while the relatively-stationary latching-member may be carried by the lever-arm.

The preferred embodiment of the readily-releasable automatic locking-means is shown 30 in Fig. III as comprising a horizontal pivot 12 secured upon the reverse or inner face of the standard immediately above the slot 10, and a weighted cam-detent 13 journalled on said pivot to swing vertically into the 35 slot, and preferably provided with an extension constituting a handle 14. When the latch 9 is inserted into the slot, its nose pushes forwardly the depending cam-portion of the detent, and as the latch drops 40 its hook into latching-position the detent follows automatically (by gravity) and its cam-portion comes to rest upon the top of the latch approximately at or near its dead-center position. Consequently, the hook 45 cannot be disengaged without first swinging the detent out of its locking-position. To unload the car, the detent is disengaged and held up as by its handle 14, and then one or two blows will disengage the hook; where- 50 upon the weight of the load of sugar-cane forces the swing-door outwardly, rotating the turn-bar and its offsets, and discharging the load. If desired, a hole 15 may be provided in the end of said latch 9 for the 55 insertion of the hasp of a padlock.

In structures where the latch is not arranged to pivot in vertical plane, the end of its nose may be suitably beveled, and if desired the opposing face of the detent may 60 be correspondingly beveled, so that the insertion of the nose will readily lift the detent and permit the automatic locking of the latch. And, if desired, the tension of a spring may be employed for affording the 65 automatic locking-action of the detent.

Although the preferred embodiment of the broad invention has been set forth in full detail, yet it must be distinctly understood that the invention is not limited to the features of structure and arrangement 70 specifically set forth, but may be varied considerably, certain parts of the structure may be used to the exclusion of other parts, and parts may be transposed, without in any case departing from the spirit of the invention which is defined by the appended 75 claims.

The invention having thus been fully disclosed, what is claimed is:

1. The combination of a cane-car having 80 upright standards and an outwardly swinging side-door, suitable means such as a journalled turn-bar having an offset for holding said door closed, a lever-arm for actuating said door-holding means, two 85 complementary readily-engageable and readily-releasable latching-members for maintaining said lever-arm in its door-holding position, one of said latching-members being a hook-carrying latch pivoted and also laterally-movable upon a horizontal portion 90 of said lever-arm, and the other member being supported by some other part of the structure such as one of the car-standards, and readily-releasable means for automatically 95 locking said latching-members in engaged position, said means comprising a gravity-actuated cam-detent pivoted in position where it will automatically lock said complementary members when in their 100 latched-engagement.

2. The combination of a cane-car having upright standards and an outwardly swinging side-door, suitable means such as a journalled turn-bar having an offset for holding said door closed, a lever-arm for actuating said door-holding means, two complementary readily-engageable and readily-releasable latching-members for maintaining said lever-arm in its door-holding position, one of said latching-members being a hook-carrying latch pivoted and also laterally-movable upon a horizontal portion of said lever-arm, and the other member being supported by some other part of the structure such as one of the car-standards, and readily-releasable means for automatically locking said latching-members in engaged position, said means comprising a suitable detent pivoted 110 to automatically lock said latching-members in engagement.

3. The combination of a cane-car having upright standards and an outwardly swinging side-door, suitable means such as a journalled turn-bar having an offset for holding said door closed, a lever-arm for actuating said door-holding means, two complementary readily-engageable and readily-releasable latching-members for maintaining 115

- ing said lever-arm in its door-holding position, one of said latching-members being a hook-carrying latch pivoted and also laterally-movable upon a horizontal portion 5 of said lever-arm, and the other member being supported by some other part of the structure such as one of the car-standards, and readily-releasable means for automatically locking said latching-members in engaged position, said means comprising a pivoted 10 detain. 70
4. The combination of a cane-car having upright standards and an outwardly swinging-side door, suitable means such as a journaled turn-bar having an offset for holding said door closed, a lever-arm for actuating said door-holding means, two complementary readily-engageable and readily-releasable latching-members for maintaining 15 said lever-arm in its door-holding position, one of said latching-members being so mounted so as to be pivotable in a plane and also to be movable in another direction with respect to said plane, and readily-releasable means for automatically locking 20 said latching-members in engaged position, 75 said means comprising a gravity-actuated cam-detent pivoted in position where it will automatically lock said complementary members when in the latched-engagement. 80
5. The combination of a cane-car having upright standards and an outwardly swinging-side door, suitable means such as a journaled turn-bar having an offset for holding said door closed, a lever-arm for actuating said door-holding means, two complementary readily-engageable and readily-releasable latching-members for maintaining 25 said lever-arm in its door-holding position, one of said latching-members being so mounted so as to be pivotable in a plane and also to be movable in another direction with respect to said plane, and readily-releasable means for automatically locking 30 said latching-members in engaged position, 85 said means comprising a gravity-actuated cam-detent pivoted in position where it will automatically lock said complementary members when in the latched-engagement. 90
6. The combination of a cane-car having upright standards and an outwardly swinging-side door, suitable means such as a journaled turn-bar having an offset for holding said door closed, a lever-arm for actuating said door-holding means, two complementary readily-engageable and readily-releasable latching-members for maintaining 35 said lever-arm in its door-holding position, one of said latching-members being so mounted so as to be pivotable in a plane and also to be movable in another direction with respect to said plane, and readily-releasable means for automatically locking 40 said latching-members in engaged position, 95 said means comprising a suitable detent pivoted to automatically lock said latching-members in engagement. 100
7. The combination of a cane-car having upright standards and an outwardly swinging-side door, suitable means such as a journaled turn-bar having an offset for holding said door closed, a lever-arm for actuating said door-holding means, two complementary readily-engageable and readily-releasable latching-members for maintaining 45 said lever-arm in its door-holding position, one of said latching-members being so mounted so as to be pivotable in a plane and also to be movable in another direction with respect to said plane, and readily-releasable means for automatically locking 50 said latching-members in engaged position, 105 said means comprising a suitable detent pivoted to automatically lock said latching-members in engagement. 110
8. The combination of a cane-car having upright standards and an outwardly swinging-side door, suitable means such as a journaled turn-bar having an offset for holding said door closed, a lever-arm for actuating said door-holding means, two complementary readily-engageable and readily-releasable latching-members for maintaining 55 said lever-arm in its door-holding position, one of said latching-members being so mounted so as to be pivotable in a plane and also to be movable in another direction with respect to said plane, and readily-releasable means for automatically locking 60 said latching-members in engaged position, 115 said means comprising a suitable detent pivoted to automatically lock said latching-members in engagement. 120
9. The combination of a cane-car having upright standards and an outwardly swinging-side door, suitable means such as a journaled turn-bar having an offset for holding said door closed, a lever-arm for actuating said door-holding means, two complementary readily-engageable and readily-releasable latching-members for maintaining 65 said lever-arm in its door-holding position, one of said latching-members being so mounted so as to be pivotable in a plane and also to be movable in another direction with respect to said plane, and readily-releasable means for automatically locking 70 said latching-members in engaged position, 125 said means comprising a suitable detent pivoted to automatically lock said latching-members in engagement. 130

- 5   mentary readily-engageable and readily-releasable latching-members for maintaining said lever-arm in its door-holding position, said members being supported respectively on the lever-arm and on some other part of the structure, and readily-releasable means for automatically locking said latching-members in engaged position, said means comprising a gravity-actuated cam-detent pivoted in position where it will automatically lock said complementary members when in their latched-engagement.

10   11. The combination of a cane-car having upright standards and an outwardly swinging side-door, suitable means such as a journalled turn-bar having an offset for holding said door closed, a lever-arm for actuating said door-holding means, two complementary readily-engageable and readily-releasable latching-members for maintaining said lever-arm in its door-holding position, said members being supported respectively on the lever-arm and on some other part of the structure, and readily-releasable means for automatically locking said latching-members in engaged position.

15   12. The combination of a cane-car having upright standards and an outwardly swinging side-door, suitable means such as a journalled turn-bar having an offset for holding said door closed, a lever-arm for actuating said door-holding means, two complementary readily-engageable and readily-releasable latching-members for maintaining said lever-arm in its door-holding position, said members being supported respectively on the lever-arm and on some other part of the structure, and readily-releasable means for automatically locking said latching-members in engaged position.

20   13. The combination of a cane-car having upright standards and an outwardly swinging side-door, suitable means such as a journalled turn-bar having an offset for holding said door closed, a lever-arm for actuating said door-holding means, two complementary readily-engageable and readily-releasable latching-members for maintaining said lever-arm in its door-holding position, said members being supported respectively on the lever-arm and on some other part of the structure, and readily-releasable means for automatically locking said latching-members in engaged position.

25   14. The combination of a cane-car having upright standards and an outwardly swinging side-door, suitable means such as a journalled turn-bar having an offset for holding said door closed, a lever-arm for actuating said door-holding means, two complementary readily-engageable and readily-releasable latching-members for maintaining said lever-arm in its door-holding position, one of said latching-members being a hook-carried latch pivoted and also laterally-movable upon a horizontal portion of said lever-arm, and the other member being supported by some other part of the structure such as one of the car-standards, and readily-releasable means for automatically locking said latching-members in engaged position.

30   15. The combination of a cane-car having upright standards and an outwardly swinging side-door, suitable means such as a journalled turn-bar having an offset for holding said door closed, a lever-arm for actuating said door-holding means, two complementary readily-engageable and readily-releasable latching-members for maintaining said lever-arm in its door-holding position, one of said latching-members being so mounted so as to be pivotable in a plane and also to be movable in another direction with respect to said plane, and readily-releasable means for automatically locking said latching-members in engaged position.

35   16. The combination of a cane-car having upright standards and an outwardly swinging side-door, suitable means such as a journalled turn-bar having an offset for holding said door closed, a lever-arm for actuating said door-holding means, two complementary readily-engageable and readily-releasable latching-members for maintaining said lever-arm in its door-holding position, said members being supported respectively on the lever-arm and on some other part of the structure, and readily-releasable means for automatically locking said latching-members in engaged position.

40   17. The combination of a cane-car having upright standards and an outwardly swinging side-door, suitable means such as a journalled turn-bar having an offset for holding said door closed, a lever-arm for actuating said door-holding means, two complementary readily-engageable and readily-releasable latching-members for maintaining said lever-arm in its door-holding position, and readily-releasable means for automatically locking said latching-members in engaged position, said means comprising a gravity-actuated cam-detent pivoted in position where it will automatically lock said complementary members when in their latched-engagement.

45   18. The combination of a cane-car having upright standards and an outwardly swinging side-door, suitable means such as a journalled turn-bar having an offset for holding said door closed, a lever-arm for actuating said door-holding means, two complementary

readily-engageable and readily-releasable latching-members for maintaining said lever-arm in its door-holding position, and readily-releasable means for automatically

5 locking said latching-members in engaged position, said means comprising a suitable detent pivoted to automatically lock said latching-members in engagement.

19. The combination of a cane-car having 10 upright standards and an outwardly swinging side-door, suitable means such as a journaled turn-bar having an offset for holding said door closed, a lever-arm for actuating said door-holding means, two complementary 15 readily-engageable and readily-releasable latching-members for maintaining said lever-arm in its door-holding position, and readily-releasable means for automatically locking said latching-members in engaged 20 position, said means comprising a pivoted detent.

20. The combination of a cane-car having upright standards and an outwardly swinging side-door, suitable means such as a journaled turn-bar having an offset for holding 25 said door closed, a lever-arm for actuating said door-holding means, two complementary readily-engageable and readily-releasable latching-members for maintaining said lever-arm in its door-holding position, and readily-releasable means for automatically locking said latching-members in engaged 30 position.

21. The combination of a cane-car having 35 upright standards and an outwardly swinging side-door, suitable means such as a journaled turn-bar having an offset for holding said door closed, a lever-arm for actuating said door-holding means, two complementary 40 readily-engageable and readily-releasable latching-members for maintaining said lever-arm in its door-holding position, one of said latching-members being a hook-carrying latch pivoted and also laterally-

movable upon a horizontal portion of said 45 lever-arm, and the other member being supported by some other part of the structure such as one of the car-standards.

22. The combination of a cane-car having upright standards and an outwardly swinging 50 side-door, suitable means such as a journaled turn-bar having an offset for holding said door closed, a lever-arm for actuating said door-holding means, two complementary 55 readily-engageable and readily-releasable latching-members for maintaining said lever-arm in its door-holding position, one of said latching-members being a hook pivoted and also laterally-movable on its supporting journal, and the other member being supported by some other part of the structure such as one of the car-standards. 60

23. The combination of a cane-car having upright standards and an outwardly swinging side-door, suitable means such as a journaled turn-bar having an offset for holding 65 said door closed, a lever-arm for actuating said door-holding means, two complementary readily-engageable and readily-releasable latching-members for maintaining said 70 lever-arm in its door-holding position, one of said latching-members being so mounted so as to be pivotable in a plane and also to be movable in another direction with respect to said plane. 75

24. The combination of a cane-car having upright standards and an outwardly swinging side-door, suitable means such as a journaled turn-bar having an offset for holding 80 said door closed, a lever-arm for actuating said door-holding means, two complementary readily-engageable and readily-releasable latching-members for maintaining said lever-arm in its door-holding position, one of said members being relatively movable in 85 more than one plane.

OTIS T. GREGG.
